Arthur J. Canfield Co.
Atty.

UNITED STATES PATENT OFFICE.

ARTHUR J. CANFIELD, OF MONTREAL, QUEBEC, CANADA.

METHOD OF MAKING DRAFT-GEAR YOKES.

1,349,493.

Specification of Letters Patent. Patented Aug. 10, 1920.

Application filed March 25, 1920. Serial No. 368,509.

To all whom it may concern:

Be it known that I, ARTHUR J. CANFIELD, a citizen of the United States, and resident of the city of Montreal, in the Province of Quebec and Dominion of Canada, have invented certain new and useful Improvements in Methods of Making Draft-Gear Yokes, of which the following is a full, clear, and exact description.

10 This invention relates to improvements in method or process of making draft gear yokes, and the object of the invention is to provide an inexpensive and expeditious method of manufacturing yokes in one piece without any seams or joints, so as to comply with M. C. B. regulations.

15

According to the present invention, a billet is pierced so as to form a tubular or hollow body closed at one end. This tubular body is flattened either during formation or subsequently and is then formed by various operations performed in suitable sequence, preferably into a finished yoke.

In the drawings which illustrate the invention—

Figures 1 to 5 inclusive are perspective views illustrating various stages of the completed yoke.

Fig. 6 is a perspective view of the completed yoke.

Referring more particularly to the drawings, 11 designates a tubular or hollow body closed at the end 12 and open at the opposite end 13. The body in some stage of manufacture is flattened in cross section, as shown for example in Fig. 2, thus providing two opposite flat sides 14 that may be termed top and bottom, the bottom being of course invisible, and two remaining sides 15. The thickness from top to bottom and, if desired, the width from side to side may be slightly greater in a portion 16 toward the open end. This enlargement permits an enlargement of the bore, so that the depth of the bore in

45 the enlarged portion may be substantially equal to the over-all depth in the remaining portion. The top and bottom of the enlarged portion 16 form jaws 17 adapted to embrace the shank of a coupler. The jaws 50 may be thickened to form bosses 18 at the outer ends of and, if desired, surrounding the key slots 19. The top and bottom are provided with openings 20 to permit insertion of the draft gear.

55 In making the yoke, a billet or the like,

either round or rectangular in cross section, is placed in a suitable die and pierced to produce the tubular body 11. The body when first pierced may be of the cylindrical shape shown in Fig. 1 and may be afterward flattened to the form shown in Fig. 2, or may be primarily formed to substantially the shape shown in Fig. 2, thus omitting the step shown in Fig. 1. The possibility of producing a form substantially as shown in Fig. 2 at the first operation depends upon the temperature and the quality of material and also upon the shape of the billet. If billets round or square in cross section are used, it will be probably necessary to pierce the billet to the form shown in Fig. 1 and then flatten the pierced billet to produce the form shown in Fig. 2. If a rectangular billet having unequal diameters is used, it will be possible to produce a form substantially as shown in Fig. 2 at the first operation. The body may also be formed under these conditions with its sides flat, as shown in Fig. 4, instead of rounded, as shown in Fig. 2, thus eliminating a subsequent operation of flattening the sides. It will be noted that the flattened body shown in Fig. 2 is of greater depth adjacent its open end than adjacent its closed end.

The enlarged portion of the flattened body toward the open end is now cut away at the sides by any suitable means such as shearing or burning with an oxyacetylene flame or electric arc. This resolves the bottom and top of the body into separate and distinct jaws of approximately suitable profile. 85 90

The body is then placed in suitable dies and the jaws 17 upset or thickened at their extremities to form bosses 18, the jaws being at the same time slightly sprung apart if desired. During this operation, the sides 15 of the body may be flattened if this has not been already done. 95

The formed and upset body is now placed 100 in a punch press and the key slots 19 punched through the bossed or thickened parts of the jaws 17, as shown in Fig. 5. It will be understood that it is not necessary for the bosses to surround the slots as long 105 as sufficient thickness of metal is maintained at the ends of the jaws. Therefore bosses at the tips of the jaws reaching only to the outer ends of the slots will in many cases be sufficient. 110

The top and bottom of the flattened body between the enlarged part 16 and the closed end 12 are now cut away to substantially the extent shown in Fig. 6, forming openings 20 through which the draft gear may be inserted. This cutting out of the top and bottom may be done in any suitable manner, such as previously indicated in connection with the forming of the jaws, but 10 is preferably done mechanically in order that finished edges and a definite size of opening will be produced.

While the various steps of the process have been described in a certain order, it 15 will be understood that the invention is not confined to this particular order of the steps. For example, the punching of the slots 19 may be performed after the formation of the openings 20.

20 From the foregoing description, it will be seen that the yoke is produced from a single piece of metal without seam or joint of any description and therefore complies with M. C. B. requirements. Owing to the fact 25 that the yoke is forged from a single piece of metal, the maximum strength will be obtained and any flaws or soft spots in the metal will be eliminated, so that the finished yokes will be of uniform strength.

30 Having thus described my invention, what I claim is:—

1. A method of making draft gear yokes and the like, which comprises piercing a 35 billet to form a hollow body open at one end and closed at the other end, forming jaws at the open end of the body, and opening the body between said jaws and the closed end of the body for the reception of draft gear.

40 2. A method of making draft gear yokes and the like, which comprises piercing a billet to produce a hollow body open at one end and closed at the other end, forming

jaws at the open end of said body, thickening said jaws by upsetting, slotting the jaws 45 in their thickened portions, and opening the body at opposite sides between the jaws and the closed end of the body.

3. A method of forming draft gear yokes and the like, which comprises piercing a 50 billet to produce a hollow body open at one end and closed at the other end, rough-forming jaws at the open end of said body by removing diametrically opposite portions of the metal, and finally shaping the jaws 55 by upsetting and opening the body between the jaws and the closed end of the body.

4. A method of making draft gear yokes, which comprises forging a billet to produce a hollow body rectangular in cross section 60 and closed at one end and open at the other end, forming jaws at opposite sides of the open end of said billet, and opening the sides of the billet carrying the jaws.

5. A method of making draft gear yokes 65 and the like, which comprises piercing a billet to produce a hollow body closed at one end and open at the other end, flattening the body to form top, bottom and side 70 surfaces, forming jaws on the top and bottom surfaces by cutting away the material of the side surfaces, and opening the body by cutting away material of the top and bottom between the jaws and the closed end.

6. A method of making draft gear yokes, 75 which comprises piercing a solid billet to produce a hollow body closed at one end and open at the other end and subsequently treating the hollow body to form jaws at the open end and openings for the draft 80 gear between said jaws and the closed end of the body.

In witness whereof, I have hereunto set my hand.

ARTHUR J. CANFIELD.
